US00D872033S

(12) **United States Design Patent** (10) Patent No.: US D872,033 S
Morelli et al. (45) Date of Patent: ** Jan. 7, 2020

(54) CONNECTION MODULE

(71) Applicant: **Telit Communications S.p.A.**, Sgonico (Trieste) (IT)

(72) Inventors: **Andrea Morelli**, Cagliari (IT);
Antonino Sgroi, Trieste (IT); **Bruno Vittori**, Sagrado (IT); **Carlo Antonini**, Trieste (IT); **Claudio Deltin**, Grado (IT)

(73) Assignee: **Telit Communications S.p.A.**, Sgonico (Trieste) (IT)

(**) Term: 15 Years

(21) Appl. No.: 29/663,429

(22) Filed: Sep. 14, 2018

(51) LOC (12) Cl. 13-03

(52) U.S. Cl.

USPC D13/147

(74) *Attorney, Agent, or Firm* — Pearl Cohen Zedek Latzer Baratz LLP

CLAIM

The ornamental design for a connection module, as shown and described.

DESCRIPTION

FIG. 1 is a top, front, right side perspective view of a connection module showing our new design; FIG. 2 is a bottom plan view thereof; FIG. 3 is a top plan view thereof; FIG. 4 is a right side elevation view thereof; FIG. 5 is a left side elevation view thereof; FIG. 6 is a back elevation view thereof; FIG. 7 is a front elevation view thereof; and, FIG. 8 is a bottom, back, left side perspective thereof. The broken lines show portions of the connection module that form no part of the claimed design.

1 Claim, 5 Drawing Sheets
